UNITED STATES PATENT OFFICE.

FRANK A. SIMONDS, OF GRAND RAPIDS, MICHIGAN, ASSIGNOR TO SIMONDS HEATING AND SPECIALTY COMPANY, OF FREMONT, MICHIGAN, A CORPORATION OF MICHIGAN.

VACUUM STEAM-CONTROLLER.

No. 921,172.

Specification of Letters Patent.

Patented May 11, 1909.

Application filed June 15, 1907. Serial No. 379,271.

To all whom it may concern:

Be it known that I, FRANK A. SIMONDS, a citizen of the United States of America, residing at Grand Rapids, in the county of Kent and State of Michigan, have invented certain new and useful Improvements in Vacuum Steam-Controllers; and I do hereby declare the following to be a full, clear, and exact description of the invention, such as will enable others skilled in the art to which it appertains to make and use the same.

My invention relates to improvements in vacuum steam controllers, and more particularly to devices for controlling the steam in vacuum heating systems.

In a steam heating system known as the vacuum type, in which there is maintained a low pressure or vacuum in the return portion of the system, should the pressure rise in the return side from any cause such as stoppage of the pump, the water of condensation will accumulate in the system, whereby the same will be flooded.

The object of my present invention is to prevent this result by means of a device adapted to automatically shut off the supply of steam to the system whenever the pressure rises in the return side of the system from any cause, and it consists essentially of a pressure motor adapted to close the supply valve and communicating with the return side of the heating system and controlled by the condition of the pressure therein, whereby when such pressure rises, the valve will be closed and the supply of steam to the system will be cut off, and said valve will again be permitted to open when the pressure in the return side is sufficiently reduced to properly remove the water of condensation from the system; and to provide the device with various new and useful features, as hereinafter more fully described and particularly pointed out in the claims.

My invention consists essentially of a reciprocating member connected to the supply valve and normally adapted to close the same, one side of said member being exposed to atmospheric pressure to hold it out of action, and at the other side being in communication with the return side of the heating system, whereby the said atmospheric pressure is unbalanced, according to the like condition in the said return side, as will more fully appear by reference to the accompanying drawings, in which:

Figure 1. represents a steam heating plant with my device attached; Fig. 2. a side elevation of my improved regulator; and, Fig. 3. a vertical section of the same.

Like numbers refer to like parts in all of the figures.

1 represents a hollow globular body within which is a centrally located high pressure chamber 2, in which is mounted a balanced valve 3 guided by a pin 5 projecting downward from a cap 4 serving as a closure for an opening in the case through which the valve may be inserted. The valve is also provided with a downwardly projecting stem 6 inserted in a screw threaded opening in a vertically movable coupling 12 extending through a gland in a lower head 4^a attached to the body 1 and closing an opening in the lower side thereof. Pivotaly attached to the coupling 12 is a piston rod 13 extending downward through the axis of a lenticular chamber 7, in which chamber is a flexible reciprocating diaphragm 11 attached to the rod 13 and serving as a piston to move the rod. Pivoted to said rod at the lower end is a lever 14 fulcrumed on a hanger 15 extending downward from the chamber 7, and on this lever are adjustable weights 16 and 17 to adapt the action of the device to different pressures, as hereafter described. Communicating with the interior of the body 1 is a pipe 10, which supplies steam to the various radiators of the plant, a high pressure radiator 29 and a low pressure radiator 30 being shown and connected by a pressure reducing trap 31. Extending from this pipe to the upper part of the chamber 7 and above the diaphragm 11 is a pipe 8 in which is a valve 9 to cut off the flow through said pipe in the event that the chamber 7 is to be opened up for any purpose when steam is on the plant. So far the device is a known form of pressure regulator for steam heating systems and will open and remain open whenever the pressure falls in the system.

My invention consists in the means for closing the valve whenever the normal working vacuum fails to be maintained in the return side of the system, or in other words when the pressure rises in the said return side, sufficient to prevent proper removal of the water of condensation therefrom, and consists preferably of the following means, to-wit.

Extending downward from the chamber 7

are hangers 21 upon the lower ends of which is mounted a second lenticular chamber 18 preferably of smaller size than the chamber 7 and in which is a corresponding flexible reciprocating diaphragm 19 also serving as a piston to which the rod 23 is attached. Communicating with the upper side of this chamber, and above the diaphragm is a pipe 20 which extends to the return side of the system in which is maintained a vacuum by the usual means of a pump 34 having its steam end 35 connected to the boiler 27 by a pipe 36. This vacuum at the upper side thereof permits the air pressure below to raise this diaphragm to the upper part of the chamber. To the rod 23 is pivoted a lever 24 fulcrumed on a hanger 22 extending downward from the under side of the chamber. On this lever 24 is an adjustable weight 25 to oppose the upward tendency of the diaphragm 19. Connecting the levers 24 and 14 is a chain 26, which is normally somewhat slack and which serves to bring the action of the weight 25 upon the lever 14 whenever the air pressure in the chamber 18 fails to sustain the diaphragm 19 in its upper position. The weights 16 and 17 are adjusted to hold the balanced valve open under the required flow of steam and pressure in the pipe 10 and in the heating system. Should the pressure, however, rise above that which the adjustment is for, steam will flow back through the pipe 8 and increasing the pressure upon the upper side of the diaphragm 11 will lower the valve and thus reduce the flow of steam and reduce the pressure in the radiators.

So far the described operation of the device is old, and it provides only for cutting off excessive pressure in the radiators. The defect of the same which my device remedies is that should the steam pressure in the boiler run down too low or otherwise fail to operate the pump, the same would fail to remove the water and maintain the vacuum in the return side and the heating plant would become flooded with condensation water. With the device shown, however, the diaphragm 19 is normally held in elevated position with the weight 25 elevated and the chain 26 slack, but should the vacuum on the return side be reduced from any cause, the atmospheric pressure below the diaphragm 19 will be so nearly balanced that the diaphragm will not be supported and the weight 25 acting through the chain 26 will close the balanced valve and shut off the steam. So also when the plant is shut down, the balanced valve is automatically closed in like manner and remains closed until steam is raised in the boiler and a vacuum is formed upon the return side of the system by starting the pump. The steam is thus automatically shut off whenever there is an insufficient differential in pressures either by insufficient steam pressure on the supply side

or insufficient vacuum on the return side, to operate the system properly and again automatically turned on when sufficient differential is restored to properly operate the system.

70

What I claim is:

1. In combination with a steam heating system having a separate supply pipe for the heating medium, a separate return pipe for the condensation, a valve in the supply pipe and means for maintaining a vacuum in the return pipe; two separate pressure motors connected to the valve to separately close the same, one of said motors being in communication with the supply pipe and the other motor being in communication with the return pipe and each independently operated to close said valve by increase of pressure in the respective pipe.

75 2. In combination with a steam heating system having a separate supply pipe for the heating medium, a separate return pipe for the condensation, a valve in the supply pipe and means for maintaining a vacuum in the return pipe; a pressure regulator in the supply pipe adapted to open when the pressure falls in the said pipe, a weight connected to said regulator to close the same, and a pressure motor connected to the weight to support the same, said motor being in communication with the return pipe at one side and the atmosphere at the other side and operated to support the weight by the unbalanced atmospheric pressure therein due to the vacuum in the return pipe.

80 3. A steam heating system comprising a radiator, a supply pipe communicating with the radiator, a valve in the supply pipe, a separate return pipe communicating with the radiator, a pump communicating with the return pipe to maintain a vacuum therein, means for operating said pump, a pressure motor communicating with the supply pipe and with the atmosphere and connected to said valve to open the same by atmospheric pressure and to close the same by pressure from the supply pipe and a second pressure motor communicating with the return pipe and the atmosphere and also connected to said valve to close the same by pressure from the return pipe and held out of operation by atmospheric pressure.

85 4. A steam heating system comprising a radiator, a supply pipe and a return pipe, each communicating with the radiator, means for maintaining a vacuum in the return pipe; a valve in the supply pipe, means for automatically closing the said valve when the pressure increases in the supply pipe and separate means for closing said valve when the vacuum is reduced in the return pipe.

90 5. A steam heating system comprising a radiator, a supply pipe and a return pipe each communicating with the radiator,

means for removing atmospheric pressure from the return pipe and maintaining a vacuum therein, a balanced valve in the supply pipe, two separate and independently operative pressure motors each having a reciprocating member connected to the valve to operate the same, one of said motors operated by the pressure in the supply pipe to close the valve, and the other motor operated by decrease of vacuum in the return pipe to close the valve.

6. A steam heating system comprising a radiator, a supply pipe and a return pipe each communicating with the radiator, means for removing atmospheric pressure from the return pipe, a balanced valve in the supply pipe to control the flow therethrough, two separate flexible diaphragms connected to the said valve to close the same, one side 15 of each diaphragm being exposed to the atmospheric pressure, a closed chamber at the other side of each diaphragm and closed thereby, one of said chambers being in open communication with the supply pipe at a 20 point between the valve and the radiator, and the other chamber being in open communication with the return pipe between the 25 radiator and the pump.

7. In a steam heating system, the combination of a boiler, a radiator, a vacuum 30 pump, a supply pipe communicating with the boiler and radiator, a steam pipe communicating with the boiler and the pump, a return pipe communicating with the radiator and the pump, a balanced valve in the supply pipe, a reciprocating member connected 35 to the valve to open and close the same, a closed chamber above the said member, a

pipe forming an open passage between the said chamber and the supply pipe at a point 40 between the valve and the radiator, an auxiliary weight connected to the said member to close the valve, a second reciprocating member connected to the weight to support the same by atmospheric pressure, a closed 45 chamber above said member and a pipe forming an open passage between the said chamber and the return pipe.

8. In a steam heating system the combination of a boiler, a radiator, a vacuum 50 pump, a supply pipe communicating with the boiler and radiator, a return pipe communicating with the radiator and pump, a steam pipe communicating with the boiler and pump, a balanced valve in the supply 55 pipe, a flexible diaphragm connected to the valve and exposed to atmospheric pressure at the lower side, a closed chamber above the diaphragm, a pipe forming an open passage between said chamber and the supply pipe 60 at a point between the valve and radiator, a second flexible diaphragm exposed to atmospheric pressure at the lower side, a closed chamber above the said diaphragm, a pipe forming an open passage between the 65 said chamber and the return pipe, a separate weight connected to each diaphragm and supported thereby, and means for connecting each weight to the valve to close the same.

In testimony whereof I affix my signature 70 in presence of two witnesses.
